UNITED STATES PATENT OFFICE.

CURT STILLE, OF ZEHLENDORF-WEST, NEAR BERLIN, GERMANY.

ELECTROPNEUMATIC SOUND-BOX.

1,132,404.

Specification of Letters Patent. Patented Mar. 16, 1915.

Application filed April 24, 1913. Serial No. 763,377.

To all whom it may concern:

Be it known that I, CURT STILLE, doctor of philosophy, of Zehlendorf-West, a subject of the King of Prussia, and whose post-office address is 4/5 Bülowstrasse, Zehlendorf-West, near Berlin, Kingdom of Prussia, German Empire, have invented a new and useful Electropneumatic Sound-Box, of which the following is a specification.

10 This invention relates to an electro-pneumatic sound box, that is to say a sound box in which air is forced from a pressure reservoir or through fans and the like, through the box, and in which there is provided a 15 grating, the openings of which are regulated by an electro-magnet which is supplied with telephone current or the like.

In the accompanying drawings one form of this improved sound box is shown by way 20 of example, in which:-

Figure 1 is a diagrammatic view of the arrangement of the said box, and Figs. 2 and 3 are views of details.

The box D is provided with an opening 25 B for the sound, and with an outlet opening C. In the center there is arranged a diaphragm F provided with longitudinal slits s, which in Fig. 1 can only be seen in section, while in Fig. 3 they are drawn to 30 a larger scale. Above the diaphragm disk F which may consist of brass or the like, there is arranged the small plate m which is provided with slits s' which correspond to the slits s. The aforesaid plate is adapted 35 to move along bars and is held in suspension by the adjustable springs q r. To the plate m there is secured a knee-shaped piece or bend k which terminates in the armature a. Opposite this armature there is arranged 40 an electro-magnet l. The distance separating the said electro-magnet from its armature is regulated by a micrometer screw r.

The diaphragm together with its slits is shown in detail in Fig. 2, while the slits 45 are shown separately, partly in section and partly in perspective in Fig. 3, which is drawn to a larger scale.

The mode of operation of the apparatus is as follows:—When telephonic or the like 50 currents are sent through the electromagnet l and if the apparatus is adjusted so as to be sensitive, the air which passes through the apparatus reproduces, under the influence of the variation of the openings in

the grating, the sounds which correspond 55 to the currents. The improved apparatus has not only the important advantage that it has a very loud sound, but that it reproduces vibrations, particularly of musical notes, in a perfect manner.

What I do claim as my invention, and desire to secure by Letters Patent of the United States, is:—

1. In a sound transmitting apparatus the combination of a casing providing an air 65 blast passage, a stationary grate mounted in said casing, a movable grate associated with said stationary grate, and a sound transmitting electro-magnet associated with said movable grate and controlling the 70 operation thereof.

2. In a sound transmitting apparatus the combination of a casing providing an air 75 blast passage, a diaphragm mounted in said casing and having a grate section, a movable grate mounted on said diaphragm, and a sound transmitting electro-magnet associated with said movable grate and controlling the operation thereof.

3. In a sound transmitting apparatus the 80 combination of a casing providing an air blast passage, a diaphragm mounted in said casing and having a grate section, a movable grate having flexible suspension on said diaphragm and disposed immediately adjacent the grate section thereof, and a sound transmitting electro-magnet for imparting rectilinear vibratory motion to said movable 85 grate.

4. In a sound transmitting apparatus the 90 combination of a casing providing an air blast passage, a diaphragm mounted in said casing and having a grate section, a movable grate having flexible suspension on said diaphragm and disposed immediately adjacent the grate section thereof, and a sound transmitting electro-magnet mounted on the diaphragm and having its armature mounted on the movable grate for imparting rectilinear vibratory motion to said movable 95 grate.

In testimony whereof I have hereunto set my hand in presence of two subscribing witnesses.

CURT STILLE.
